(57) **CLAIM**

The ornamental design for a container for food packages, as shown and described.

DESCRIPTION

FIG. 1 is a perspective view of a container for food packages showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an enlarged view of the container for food packages taken from the circled portion in FIG. 1.

In FIGS. 1 and 8, the dotted circle illustrate the environment of the container for food packages which forms no part of the claimed design.

The broken lines in the bands and the parallel broken lines in the container for food packages depict stitching lines and form no part of the claimed design.
